UNITED STATES PATENT OFFICE.

ROBERT R. WEAVER, OF CHICAGO, ILLINOIS, ASSIGNOR TO GENERAL AMERICAN TANK CAR CORPORATION, OF CHICAGO, ILLINOIS, A CORPORATION OF WEST VIRGINIA.

UNDERFRAME FOR CARS.

Application filed June 5, 1922. Serial No. 565,858.

To all whom it may concern:

Be it known that I, ROBERT R. WEAVER, a citizen of the United States, residing at Chicago, in the county of Cook and State 5 of Illinois, have invented a new and useful Improvement in Underframes for Cars, of which the following is a specification.

My invention relates to under-frames of cars, formed with so-called center sills 10 which extend lengthwise of the car and substantially midway between the opposite sides thereof, and more particularly to center sills of the type comprising a body portion presenting relatively widely horizontally spaced side walls operatively connected 15 together at the upper surface of the sill, and a member having upper and lower flanges extending lengthwise of the sill and connected with the body portion of the latter, my pending application for United States Letters Patent, Serial, No. 508,139, filed October 17, 1921, now Patent No. 1,420,352, dated June 20, 1922, disclosing a sill of the general type above referred to.

As a premise to the following, it may be stated that the particular type of sill referred to, where the side walls of the body portion converge upwardly, is more commonly used in railway cars of the drop-bottom type wherein the bottom of the car is formed with a series of plates generally one series at each side of the center line of the car and hingedly supported to the center sill substantially at the center line, the center sill being formed with the upwardly converging side walls, as stated, for the purpose of rendering the upper surface of the sill of as narrow a width as possible in order to permit of the hinging of the door-

40 forming plates as close to the center line of the car as possible, and to reduce, as much as possible, the presentation by the center sill of a surface upon which the material loaded into the car may be, retained in the 45 dumping operation.

It may be stated as a premise to the following, that center sills of the type above referred to and involving as parts thereof, the upper and lower flanged beams, present 50 great advantages over center sills of the

general type stated and not employing I-beams as set forth in my application above stated; and it is my primary object to provide a construction of center sill of the type above referred to and employing an upper 55 and lower flanged beam forming a top member, which will present the advantages above referred to and in addition thereto permit of the depth of sill being varied to suit various conditions, merely by selecting a top 60 member of sufficient depth to suit the conditions presented, while providing the bottom member of the sill of a standard size; to reduce the thickness of the sill adjacent its upper edge; to permit of the provision 65 of the sill either as of the straight type or the fish belly type, as desired; and in accordance with the preferred embodiment of my invention to permit of the body, or lower, member of the sill being made in one 70 operation and relatively inexpensively.

Figure 1 is a broken plan view of one end of a car underframe embodying my invention, the hingedly-supported plates forming the bottom of the car and the hinges for the 75 same being omitted. Fig. 2 is an enlarged section taken at the line 2 on Fig. 1 and viewed in the direction of the arrow. Fig. 3 is a sectional view of the center sill of the car and one of the bottom-forming hinged 80 plates, illustrating the manner of mounting the plates on the center sill. Fig. 4 is a broken section taken at the line 4 on Fig. 2 and viewed in the direction of the arrow. Fig. 5 is a broken section taken at the line 85 5 on Fig. 4 and viewed in the direction of the arrow; and Fig. 6, a cross-sectional view of a modification of the sill of the preceding figures.

Referring to the general arrangement 90 shown in Fig. 1, the center sill of the underframe therein shown is represented generally at 7, and connected with this center sill, to extend transversely thereof, and in spaced relation to each other, is a series of 95 cross-frame members, one of these end members at the end of the car shown in Fig. 1 being represented at 8, a bolster-forming cross-frame member at 9, it being understood that the members 8 and 9 would be dupli- 100

cated at the other end of the frame, and intermediate cross-frame members at 10. The ends of the cross-members 8, 9 and 10 are connected with angle-iron side-frame members 11 in accordance with common practice, the side wall (not shown) of the car being secured to the marginal portions of the framework thus provided.

The car shown is of the drop-bottom type, its bottom being formed of two series of plates arranged at opposite sides of the center line of the car and hingedly connected therewith to swing from substantially horizontal carrying position, to downwardly-inclined, dumping position, each series of plates extending lengthwise of the car frame, and being located within the spaces provided between the center sills 7, the side members 11, and the various cross-members 8, 9 and 10. The center sill structure shown, which is of box girder form, is formed of a lower hollow, box-like member represented generally at 12, which extends lengthwise of the car and the full length of the latter, this member being shown as formed of the section 13 provided as an integral structure and affording side walls 14 spaced apart with their upper portions, represented at 15, converging upwardly and united with the other upper top section 16. The member 12 also comprises the angle-bars 17, which form the bottom chords of the structure, these angle-bars being connected at their vertical flanges 18 with the side walls 14, in any suitable way, as by the rivets represented at 19, the member 12 also comprising a bottom cover-plate, represented at 20, shown as riveted at 21 to the horizontal flanges 22 of the angle-bars 17.

40 The center sill structure also comprises, in the particular illustrated embodiment of my invention, an I-beam, represented at 23, this beam surmounting at its lower flange 24 the top portion 16 of the member 12 to which it is rigidly secured, as by a series of rivets 25.

Located within the structure, above described, of the sill, is a series of spreader elements represented at 26, these spreader elements, which extend transversely of the sill and are located at intervals along the latter, being positioned therein coincident with the various cross-members therein referred to. The spreader elements are preferably of the box-like form shown and are preferably of integral construction, affording a lower member 27, the bottom of which preferably extends flush with the under-surfaces of the lowermost edges of the walls 13, upright side portions 28 which extend flatwise against the side portions 14, upwardly-converging portions 29 which conformingly fit against the inclined portions 15 of the member 12, a top portion 30 which extends substantially horizontally and fits against

the under side of the top portion 16 of the member 12, and a plate-portion 31 from which the various portions 27, 28, 29 and 30 extend at an angle and with which they are preferably integrally formed.

The various cross-frame members referred to are of the same general construction, one of the intermediate cross-frame members being shown in detail in the drawings, and comprising plate-like portions 32, the inner ends of which, flanged at 33, conformingly fit against the sides of the center sill, as represented more particularly in Fig. 2, and to which they are riveted, as by the rivets represented at 34, 35, 36, 37, 19 and 21, these various rivets extending through apertures in the flanged portions 33 of the sections 32, through the I-beam 23, the lower flange of the latter, the side wall forming portions of the member 12, the angle-bars 17, and the bottom plate 20, all as clearly illustrated in the drawings. The sections 32 are arranged in end to end alining relation, as shown, and extending from one to the other of these sections at their undersides and across the undersides of the center sill and the spreader element, is a strap member represented at 38, which is riveted at its ends, as represented at 39, to flanges 40 provided on the lower edges of the sections 32. Such of the rivets 21 as are coincident with the strap member 38 pass through the latter, as shown in Fig. 2, and, in addition, rivets, represented at 41, pass through the flange 27, the bottom plate 20 and the strap member 38.

Each cross-frame member referred to is also formed with a plate-section 42, which extends from one side bar 11 to the other thereof, overlapping the horizontal flanges 43 of the latter to which they are secured as by rivets 44, which pass through these parts and flanges 45 provided on the upper edges of the sections 32, the member 42 being riveted at other places, at intervals, to the flanges 45, as represented at 46.

One of the movable plates, hereinbefore referred to and forming the bottom of the car, is represented at 47, it being understood that a similar plate would be located at the opposite side of the I-beam 23 and that, in the particular arrangement shown, there would be a series of these plates at each side of the I-beam. The plates 47 are hingedly connected with the center sill to extend at opposite sides thereof, as through the medium of the brackets 48, one only of which is shown, which is riveted at 49 to the vertical web of the I-beam 23 against which it flatwise extends. Each bracket 48 carries a pivot pin 50, which engages depending flanges 51 on the door-section 47, the arrangement of the doors and the hinging means referred to being such, as shown, that when the door sections are in substantially horizontal position, as represented in Fig.

3, they will form, with the upper flange of the I-beam 23, a continuous bottom for the car, and are capable of swinging to outwardly and downwardly-inclined position 5 to dump the contents of the car at the sides of the latter, the way in which these doors are releasably held in horizontal position and released to effect dumping not being shown as such are well known in the art 10 and form no part of the present invention.

Among the many advantages presented by a structure like that just described, may be mentioned that of permitting the lower hollow member of the sill, while extending the 15 full length of the car, to be provided in various forms, as for example, of uniform cross-sectional shape across its length, or of reduced cross-section at its ends, as in the case of constructions of the so-called fish 20 belly type, and still permit of the utilization of an upper and lower flanged beam extending the full length of the car, with resultant economy and efficient functioning. It will also be observed that different depths 25 of sill, as conditions may require, may be provided by selecting an I-beam of the desired cross-sectional dimensions, which are provided in a wide range of sizes in commercial use, without requiring a change in 30 the hollow member to form the lower portion of the sill. In other words, the lower portion of the sill may be standard as to size, and sills of different depths may be built by using upper and lower flanged 35 beams of different depths.

Furthermore, by providing the member 13, as stated, it may be manufactured very economically and when installed with the other parts of the sill causes the sill to function 40 in a highly desirable manner.

The construction shown in Fig. 6 is the same as that of the preceding figures except that, instead of the member 13 being formed as an integral structure, it is formed of two 45 substantially similar members, represented at 52 and 53, and comprising the parallel side wall portions 52^a and 53^a, the upwardly converging portions 52^b and 53^b and the horizontal portions 52^c and 53^c, these horizontally disposed portions being arranged 50 in overlapping position as shown, and the rivets, represented at 54, which secure the I-beam 23 to the body structure, represented generally at 12^a, passing through the 55 overlapped portions 52^c and 53^c and through the lower flange of the I-beam 23.

It will be noted that in both of the constructions illustrated, the lower hollow member of the sill, which is surmounted by the 60 flanged beam, extends continuously crosswise of, and beneath, the lower flange of this beam, the I-beam being rigidly secured at its lower flange to the top portion of the hollow body of the sill directly beneath it.

65 While I have illustrated and described

certain particular forms in which my invention may be embodied, I do not wish to be understood as intending to limit it thereto as the invention may be embodied in other forms than those shown, and the same 70 may be variously modified and altered without detracting from the spirit of my invention.

What I claim as new, and desire to secure 75 by Letters Patent, is:

1. A center sill for a car comprising side walls spaced apart and presenting upwardly converging portions, and a member having top and bottom flanges surmounting at its lower flange the top portion of the structure 80 comprising said side walls, and secured thereto.

2. A center sill for a car formed of a lower, hollow, structure extending lengthwise of the sill and an upper, relatively narrow, member having upper and lower flanges extending longitudinally of the sill, said member surmounting at its lower flange the top portion of said hollow structure and secured thereto, the portion of said hollow 85 structure directly beneath said member extending continuously beneath said lower flange crosswise of the sill.

3. A center sill for a car formed of a lower, hollow, structure extending lengthwise of the sill and an upper I-beam extending longitudinally of the sill, said I-beam surmounting at its lower flange the top portion of said hollow structure and secured thereto, the portion of said hollow structure 90 directly beneath said I-beam extending continuously beneath said lower flange crosswise of the sill.

4. A center sill for a car formed of a lower, hollow, structure extending lengthwise of the sill and presenting side walls spaced apart and upwardly converging, and an upper, relatively narrow, member having upper and lower flanges extending longitudinally of the sill, said member surmounting at its lower flange the top portion of 100 said hollow structure and secured thereto, the portion of said hollow structure directly beneath said member extending continuously beneath said lower flange crosswise of the sill.

5. A center sill for a car formed of a lower, hollow, structure extending lengthwise of the sill and presenting side walls and a top portion formed integrally, and an upper, relatively narrow, member having upper and lower flanges extending longitudinally of the sill, said member surmounting at its lower flange the top portion of 110 said hollow structure and secured thereto, the portion of said hollow structure directly beneath said member extending continuously beneath said lower flange crosswise of the 115 sill.

5. A center sill for a car formed of a lower, hollow, structure extending lengthwise of the sill and presenting side walls and a top portion formed integrally, and an upper, relatively narrow, member having upper and lower flanges extending longitudinally of the sill, said member surmounting at its lower flange the top portion of 120 said hollow structure and secured thereto, the portion of said hollow structure directly beneath said member extending continuously beneath said lower flange crosswise of the 125 sill.

6. A center sill for a car formed of a 130

lower, hollow, structure extending lengthwise of the sill and presenting side walls and a top portion formed integrally, said side walls at their upper portions converging upwardly, and an upper, relatively narrow, member having upper and lower flanges extending longitudinally of the sill,

said member surmounting at its lower flange the top portion of said hollow structure and secured thereto, the portion of said hollow structure directly beneath said member extending continuously beneath said lower flange crosswise of the sill. 10

ROBERT R. WEAVER.
